PROTECTOR RING FOR EXTERNALLY
THREADED PIPE ENDS OR THE LIKE

Edward F. Higgins, Kirkwood, Mo.

Application August 21, 1957, Serial No. 47,467

Term of patent 14 years

(Cl. D91—1)

FIG. 1

FIG. 2

FIG. 3

FIG. 4

Figure 1 is a left end elevational view of a thread protector for pipe ends or the like embodying my new design;

Figure 2 is a side elevation thereof;

Figure 3 is a right end elevation view thereof; and

Figure 4 is a sectional view taken along line 4—4 of Figure 2.

I claim:

The ornamental design of a thread protector for pipe ends or the like, substantially as shown.
